(57) **CLAIM**

The ornamental design for a light emitting diode mini-light bar, as shown and described.

DESCRIPTION

FIG. 1 is a perspective view of a light emitting diode (LED) mini-light bar (miniature light bar) of our new design.

FIG. 2 is a front elevational view of the light bar of FIG. 1, the rear elevational view being the same as the front elevational view.

FIG. 3 is a right side elevational view of the light bar of FIG. 1, the left side elevational view being the same as the right side elevational view.

FIG. 4 is a top plan view of the light bar of FIG. 1; and, FIG. 5 is a bottom plan view of the light emitting diode beacon light of FIG. 1.
